COMBINATION GLASS RETAINER AND SPOON HOLDER

Viola M. Sengstack, Washington, D. C.

Application January 22, 1957, Serial No. 44,550

Term of patent 14 years

(Cl. D36—2)

I claim:

The ornamental design for a combination glass retainer and spoon holder, as shown.
